(57) **CLAIM**

The ornamental design for a vehicle window shade, as shown and described.

DESCRIPTION

FIG. 1 is front elevational view of a vehicle window shade; FIG. 2 is a rear view of a vehicle window shade; FIG. 3 is top view of a vehicle window shade; FIG. 4 is a bottom view of a vehicle window shade; FIG. 5 is a left side view of a vehicle window shade; and, FIG. 6 is a right side view of a vehicle window shade. The dashed lines along the periphery depict stitching and form no part of the design. The cross hatch shading depicts a dark surface ornamentation and the horizontal shading depicts a light reflective surface.
